UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

LANTERN.

1,415,634.

Specification of Letters Patent.

Patented May 9, 1922.

Application filed July 11, 1921. Serial No. 483,769.

To all whom it may concern:

Be it known that I, WILLIAM S. HAMM, a citizen of the United States, and resident of Hubbard Woods, county of Cook, and State of Illinois, have invented certain new and useful Improvements in Lanterns, of which the following is a specification, and which are illustrated in the accompanying drawings, forming a part thereof.

10 The invention relates to lanterns especially adapted for the use of trainmen, and of the type forming the subject of the application for patent of William S. Hamm and Frank A. Schuetz, filed July 8th, 1919, Serial No. 309,334.

The object of the present invention is to provide, under all conditions, an adequate supply of air from the upper part of the lantern body to maintain combustion when the currents through the body are reversed from their normal upward direction; and it consists broadly in a lantern body having air induction ports above the upper end of the globe, and a perforated shield located within the body and facing such ports.

A preferred embodiment of the invention is hereinafter described, and is illustrated in the accompanying drawings, in which—

Fig. 1 is a side elevation of the lantern, the upper portion thereof being shown in central vertical section; and

Fig. 2 is a detail sectional view on the line 2—2 of Fig. 1.

The lantern comprises a base ring 10, adapted to receive an oil font carrying a burner, as 11, the base ring being provided with air induction ports 12. A transparent globe 13 is seated on the base ring, and is surmounted by a dome, generally designated by the numeral 14 and provided with the usual depending and outstanding breast 26. An inner dome 15 constitutes, in this instance, a globe-holder, and is urged downwardly by a spring 16 reacting against the top of the outer dome 14. The top of the inner dome is somewhat contracted, being flanged inward, as shown at 27, and discharges the vapors of combustion into the chamber of the outer dome, from which they escape through suitable openings. The globe is surrounded by the usual frame 17, shown as formed of wire rods and secured to the base ring and depending therefrom to form a foot piece 18. The dome is hinged to the

frame 17, as at 19, and secured in closed position by a latch 20.

The lower portion of the side walls of the inner dome 15 is provided with a series of air induction ports 21 of ample capacity to provide a supply of air to support combustion in the event of the reversal of the currents within the body, due to wind conditions or the giving of signals. A shield, generally designated by the numeral 22, is located within the dome 15 and extends obliquely upwardly and inwardly from the wall thereof in front of the ports 21 terminating below the contracted portion 27. In practice these ports are arranged in annular series, extending entirely around the dome, and consequently the shield is annular in form.

Upon a reversal of the currents through the lamp, from their normal upward direction, air enters the ports 21 and, passing over the shield, descends and supplies the necessary oxygen to maintain the flame. The upward and inward inclination of the shield, however, prevents strong wind currents from blowing down upon the flame and extinguishing it, as might be the case even though the currents were not reversed.

Under some circumstances an imperforate shield of this character will prevent sufficient air reaching the flame from above, when required, when the shield is of sufficient height to afford the required protection from strong winds. The present invention overcomes this difficulty by perforating the shield so that some air will descend without being required to first pass entirely over.

In the preferred form of construction, which is shown in the drawings, this perforation is secured by employing two annular shield plates, one of them, designated by the numeral 23, extending upwardly and inwardly from the wall of the dome and facing the ports 21, the other, 24, being mounted above it,—its lower margin overlapping and being of slightly greater diameter than the upper margin of the lower shield ring, thus providing an annular slit between the two through which a small quantity of air may enter but which will, nevertheless, be given an initial upward direction in order that when the wind is strong it will not blow directly down upon the flame with sufficient force to extinguish it. The upper shield ring 24 preferably extends above the ports

21, thereby giving the strong entering air currents an upward initial direction.

The upper shield ring 24 may be supported in any suitable manner, as by a plurality of legs 25, as many being employed as may be deemed necessary, these legs being seated either upon the lower shield ring or upon the wall of the dome.

While the construction shown and described is preferred, and, so far as now advised, is the most efficient, the invention is of sufficient scope to include any lantern structure embodying upper air induction ports and a perforated shield for guarding the flame from strong air currents, while insuring an ample supply of air from above for supporting combustion when the supply from below becomes inadequate. Various changes in detail may be made within the range of the invention.

I claim as my invention—

1. In a lantern, in combination, a dome having a series of lateral air induction ports, and a perforated shield within the dome and facing the induction ports the opening in the shield being above the induction ports, the lower end of the shield making a substantially air tight contact with the dome and the top of the shield being free to permit air currents from the ports to pass over it.

2. In a lantern, in combination, a dome having an annular series of lateral air induction ports, an annular shield extending upwardly from the wall of the dome below the ports and being inwardly inclined, and a second annular shield ring located above but spaced apart from the first-named ring, and arranged to permit currents entering the induction ports to pass over its upper margin.

3. In a lantern, in combination, a dome having an annular series of lateral air induction ports, an annular shield extending upwardly from the wall of the dome below the ports and being inwardly inclined, and a second annular shield ring located above but spaced apart from the first-named ring; adjacent margins of the two rings overlapping the upper margin of the upper ring being free to permit air currents from the induction ports to pass over it.

4. In a lantern, in combination, a dome,

having lateral air induction ports, a shield extending upwardly and inwardly from the dome wall below the ports, and having an opening guarded by an upwardly and inwardly inclined wall, the upper margin of the shield being free to permit air currents from the ports to pass over it.

60

5. A lantern having, in combination, a dome provided with a vapor outlet, and an inner dome having its upper end contracted and provided with a central flue opening, its side walls being apertured to form induction ports, and a perforated shield extending upwardly and inwardly from the side walls of the inner dome and terminating above the induction ports.

65

6. A lantern having, in combination, a globe, and a dome extending upwardly from the globe and provided at its upper end with an outlet for vapors and at its side walls with induction ports, an instanding flange between the outlet and the induction ports, and a perforated shield extending inwardly and upwardly from the side walls of the dome below the induction ports and terminating above such ports, its upper margin being free for the passage of air currents thereover.

70

7. A lantern having, in combination, a globe, and a dome extending upwardly from the globe and provided at its upper end with an outlet for vapors and at its side walls with induction ports, an instanding flange between the outlet and the induction ports, and a perforated shield extending inwardly and upwardly from the side walls of the dome below the induction ports and terminating above such ports, its upper margin being free for the passage of air currents thereover, the lower margin of the upper ring overlapping and being spaced apart from the upper margin of the lower ring.

75

8. In a lantern, in combination, a globe, a dome surrounding the globe and having air induction ports adjacent its lower end, a shield extending upwardly and inwardly from the side walls of the dome and facing the induction ports and being apertured above such ports, the upper margin of the shield being free to permit the passage of air currents thereover.
